(57) CLAIM

The ornamental design for a cup with straw, as shown and described.

DESCRIPTION

FIG. 1 is a first perspective view of a cup with straw showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof, with the straw portion removed and a closed cap portion; and,

FIG. 10 is an enlarged view of the selected portion 10 in FIG. 1.

The broken lines shown in the drawings depict portions of the cup with straw that form no part of the claimed design.
